CLAIM

We claim the ornamental design for a mounting head, as shown and described.

DESCRIPTION

FIG. 1 is a front perspective view of a mounting head in accordance with a first embodiment of our new design; FIG. 2 is a rear perspective view of the mounting head of FIG. 1;

FIG. 3 is a bottom plan view of the mounting head of FIG. 1;

FIG. 4 is a top plan view of the mounting head of FIG. 1; FIG. 5 is a right side elevation view of the mounting head of FIG. 1, the left side elevation view being a mirror image thereof;

FIG. 6 is a front elevation view of the mounting head of FIG. 1;

FIG. 7 is a rear elevation view of the mounting head of FIG. 1;

FIG. 8 is a front perspective view of a mounting head in accordance with a second embodiment of our new design; FIG. 9 is a rear perspective view of the mounting head of FIG. 8;

FIG. 10 is a bottom plan view of the mounting head of FIG. 8;

FIG. 11 is a top plan view of the mounting head of FIG. 8; FIG. 12 is a right side elevation view of the mounting head of FIG. 8, the left side elevation view being a mirror image thereof;

FIG. 13 is a front elevation view of the mounting head of FIG. 8; and,

FIG. 14 is a rear elevation view of the mounting head of FIG. 8.

The broken lines depict portions of the mounting head that form no part of the claimed design.
